Primary Examiner — Elizabeth J Oswecki*(74) Attorney, Agent, or Firm* — MH2 Technology Law Group, LLP(57) **CLAIM**

The ornamental design for indoor parcel lockers, as shown and described.

DESCRIPTION

FIG. 1 is a front perspective view of indoor parcel locker showing my new design; and,

FIG. 2 is a front elevation view thereof.

The undisclosed rear views of the indoor parcel locker shown in FIGS. 1-12 are not part of the claimed design. The broken lines in the drawings depict unclaimed environmental subject matter.
